APPARATUS FOR SUBSURFACE EXPLORATION

Ivor J. James, Jr., Bellflower, Calif., assignor to
 Union Oil Company of California, Los Angeles,
 Calif., a corporation of California

Application November 16, 1948, Serial No. 60,244

4 Claims. (Cl. 33—205)

1

This invention relates to an apparatus for the determination of data pertinent to subterranean openings such as pressure, temperature and other physical data and relates particularly to the surveying of boreholes drilled for the production of oil, gas, sulfur, water, and other materials from the subsurface. More specifically the apparatus permits determination of physical data including the borehole inclination or slope of the borehole with respect to the vertical as well as depths, pressures and temperatures and the like.

The determination of such data is especially important with respect to boreholes drilled into subsurface strata to effect recovery of valuable fluids therefrom. In some cases it is desired to deliberately drill a slanting well which deviates in a known manner from the vertical in order to supply or withdraw fluids to or from a given position in a known formation. In offshore drilling, accumulations of valuable fluids such as crude oil or others situated in strata beneath the ocean floor may be produced therefrom by deliberately drilling an inclined borehole from a shore line position. In these instances it is highly desirable to know to a significant degree of accuracy the actual inclination of the borehole so that drilling may be conducted in such a manner as to complete the well into the desired strata.

It is therefore an object of the present invention to provide an improved apparatus for determining pertinent physical data from subsurface openings.

It is a further object of this invention to provide an apparatus especially adapted to the determination of physical data from well bores drilled into the subsurface.

Another object of this invention is to provide an accurate means for the measurement of pressures, temperatures, and depths of subsurface well bores as well as their inclination from the vertical.

A more specific object of this invention is to provide an apparatus consisting of at least one variable frequency electrical oscillator, the frequency of which is altered in a known manner with the inclination of the borehole, means for transmitting this variable frequency from the well bore to the surface, and means for taking desired physical data from the variable electrical oscillation received at the surface.

Other objects and advantages of this invention will become apparent to those skilled in the art as the description thereof proceeds.

Briefly, the present invention comprises a method for determining subsurface pressures, temperatures, depths and inclinations from sub-

2

surface openings such as well bores by means of an electrical oscillator, the frequency of which is variable in accordance with at least one of the aforementioned properties of the subsurface opening. In the preferred modification of this invention the subsurface property which it is desired to determine is allowed to influence the frequency of an electrical oscillator such as one which generates electrical oscillations in the radio-frequency range. By suitably connecting the electrical oscillator or oscillators to a transmission line, the variable electrical oscillation thus produced is received and detected at the surface whereby the physical property affecting the oscillator frequency may be determined.

Specifically this invention comprises the employment of at least one variable frequency oscillator preferably generating electrical oscillations having a frequency in the radio-frequency range which extends from about 15,000 cycles per second to as high as 5,000 megacycles and higher, which oscillator is provided with a frequency determining circuit comprising an electrical inductance and an electrical capacitance. This inductance and capacitance may be connected in parallel or in series depending upon the particular modification of oscillator in which these circuit components control the oscillation frequency. The physical properties such as pressure, depth, temperature or inclination are caused to act upon this frequency determining circuit to alter the oscillation frequency in a particular manner so that the magnitude of the physical property may be determined by measuring the oscillation frequency itself or a change in the oscillation frequency.

The magnitude of the variable frequency oscillation is increased by using suitable amplifiers such as those of the vacuum tube type so that an oscillation of sufficient magnitude is obtained to permit transmitting the oscillations from the oscillator in the subsurface to a detection means in which the frequency is determined. In general it is preferable to suspend the oscillator in the subsurface in the region where the physical property desired is manifest. It is also preferable to position the detection means at the earth's surface where the variable frequency is measured in determining the physical property.

In one modification the frequency determining circuit comprises a helical coil inductance and an electrical capacitance connected in parallel to form a frequency determining circuit which may be employed in a variable frequency oscillator of the electron coupled type. To measure subsurface pressure, either the capacitance or the in-

ductance may be physically arranged to be affected by changing pressures to suitably alter the oscillation frequency in accordance therewith. To measure subsurface depths, the hydrostatic pressure exerted by a given fluid present in the subsurface opening is determined by the variable frequency oscillator and the depth may be determined by suitable direct reading instruments or by calculation. To determine subsurface temperatures, the preferred embodiment of the present invention comprises the employment of an electrical capacitance having a known capacitance-temperature relationship in conjunction with the frequency determining circuit mentioned above whereby direct exposure of the capacitance to the temperature conditions within the subsurface opening will cause the capacitance and simultaneously the frequency to vary in a known manner. To determine the inclination of the borehole from the vertical it is preferred in this invention to employ at least two variable frequency oscillators, the frequency of which changes with the inclination from a vertical position. The preferred embodiment of apparatus for measuring such inclination incorporates a pair of variable radio-frequency oscillators the frequency of which is altered by changes in capacitance of the frequency determining circuits. Preferably the capacitance is varied by the motion of at least one pendulum or other gravity sensitive member which may be employed as one electrode of the capacitances. By employing frequency determining circuits which vary in accordance with inclinations and in different planes of known relationship to each other, the determination of the individual frequencies of the oscillators or in some cases the determination of the frequency difference as well as the frequency serves to accurately determine the inclination with respect to the vertical or any other reference line. In the preferred embodiment of this invention a gyroscope control of portions of the frequency determining circuit is maintained in order that the relationship between the inclination of the subsurface opening and a given azimuth direction may be known. In one modification the gyroscope control is employed to maintain one of the variable capacitances mentioned above operating in a plane passing through a horizontal north-south line so that the radio-frequency oscillator associated with the particular variable capacitance continuously indicates the inclination in the north-south plane. A second oscillator, the variable capacitance or inductance of which is gyroscopically maintained to be actuated by physical movements acting in a second plane of known relationship to the north-south plane, permits the precise determination of inclination and azimuth readily through measurement of the frequency of the two electrical oscillators. In another embodiment of this invention gyroscopic control of a third oscillator may be obtained so that separate indications of azimuth and inclination may be obtained. Such a third oscillator may comprise an electrical oscillator generating oscillations having frequencies in the audio-frequency range extending from about ten cycles per second to more than 10,000 cycles per second. This variable audio-oscillation may be employed to modulate one of the aforementioned electrical oscillators operating in the radio-frequency range to identify that particular oscillator as well as to convey an indication of the azimuth from the exploration in-

strument to the detection means which may be positioned at the surface.

The methods and apparatus of the present invention may be more clearly understood by reference to the accompanying drawings in which:

Figure 1 shows a schematic cross section of the exploration instrument adapted to the determination of inclination and azimuth of subsurface openings such as a borehole,

10 Figure 2 shows a horizontal plan view of one disposition of the elements of the variable capacitance employed in one embodiment of the frequency determining circuits employed in the radio-frequency oscillator,

15 Figure 3 presents a simplified circuit diagram of a variable frequency oscillator adapted to the generation of electrical oscillations in the radio-frequency range,

20 Figure 4 shows an elevation view of a pair of plate type variable capacitances actuated by pendulums moving in planes disposed at a known angle to each other,

25 Figure 5 presents a simplified schematic diagram of an electrical oscillator adapted to generating electrical oscillations having frequencies in the audio-frequency range and adapted to modulate the output of one of the radio-frequency oscillators in accordance with the azimuth of the gyro control,

30 Figure 6 shows a schematic diagram of a circular variable resistance which may be associated with the gyro control to suitably vary the audio-modulation frequency in accordance with the azimuth when this type of azimuth determination is employed,

35 Figure 7 shows a vertical cross section elevation view of one embodiment of a gyroscopically controlled embodiment of the variable capacitances employed in the frequency determining circuit,

40 Figure 8 shows a plan view of the apparatus depicted in Figure 7,

45 Figure 9 shows relationships existing between oscillations received at the detecting means from the variable frequency oscillators in the exploration instrument,

50 Figure 10 shows another relationship existing between frequencies received at the detecting means from the exploration instrument,

55 Figure 11 shows a vertical cross section of part of the frequency determining circuit in which a permeability tuned variable inductance is used to vary the oscillator frequency in accordance with subsurface pressures,

60 Figure 12 shows a vertical cross section of the apparatus of Figure 11 wherein the inductance is directly varied by changing its dimensions,

Figure 13 shows the apparatus of Figure 11 wherein a variable capacitor causes frequency changes in accordance with the subsurface pressure.

65 Figure 14 shows a vertical cross section of the frequency determining apparatus wherein subsurface temperatures are measured.

66 Figure 15 shows a vertical cross section of the exploration instrument in which a pair of circular resistances shown in Figures 5 and 6 and actuated by pendulums are used to indicate inclination,

70 Figure 16 shows a plan view of the pendulum, circular resistance, and connecting gears,

75 Figure 17 represents a schematic diagram of the oscilloscope pattern obtainable from the apparatus described in conjunction with Figure 16, and

Figure 18 indicates diagrammatically a conventional wave or frequency meter for measurement of the frequency of electrical oscillations.

Referring now more particularly to Figure 1, an elevation view in cross section of one modification of apparatus for measuring inclination is shown. The constituent parts of the exploration instrument are contained in housing 10 which is suspended in the subsurface by means of suspension cable 11 which also functions as a conductor of the electrical oscillations to the surface. Housing 10 contains a pair of electrical transmission oscillators 12 and 13, a modulation oscillator 14 connected to modulate the output signal of radio-frequency oscillator 13 and thereby identify it from the output signal of radio-frequency oscillator 12, chamber 15 containing gravity sensitive member 16 such as a pendulum in proximity to stationary members 17 and 18 which are insulated from housing 10, chamber 19 containing a gyroscopically actuated member 20 provided with bearings 21 and 22 permitting member 20 to rotate freely about the longitudinal axis of housing 10 while indicating azimuth, and power supply chamber 23 containing sources of power for operating electrical constituents of the apparatus. Housing 10 is elongated and preferably of cylindrical shape having a diameter which permits it to be lowered and raised freely through a subsurface opening such as a borehole. The length of housing 10 need be only sufficient to provide volume required for constituent parts of the apparatus named above. Chamber 15 may be at least partially filled with a damping fluid to substantially eliminate the natural periodic oscillations of gravity sensitive member 16. Transformer oils are especially well suited to this purpose where high dielectric constant and the proper viscosity at the temperature of the subsurface may be obtained to limit the periodic motion.

Stationary members 17 and 18 each are connected as part of the frequency determining circuits of transmission oscillators 12 and 13 since an electrical capacitance exists between each of members 17 and 18 and gravity sensitive member 16. Thus, when the longitudinal axis of housing 10 departs from the vertical to align itself with an inclining borehole, or the like, gravity sensitive member 16 remains aligned with the vertical. The resultant movement of gravity sensitive member 16 with respect to stationary members 17 and 18 causes a change in electrical capacitance which is in proportion to the inclination of housing 10. The frequency of at least one of electrical oscillators 12 and 13 changes proportionally with the inclination to a higher or lower value.

A plan view of a cross section of the chamber containing gravity sensitive member 16 centrally situated with respect to stationary members 17 and 18 is shown in Figure 2. Connections 26, 27, and 28 are the same as those indicated in Figure 1. The angular spacing θ between stationary members 17 and 18 may be between as low as 10° to as high as 180° , but preferably this spacing is between about 60° and 150° . Spacings of 90° or 120° are representative ones which permit accurate inclination measurements.

Within chamber 15 shown in Figure 1, stationary members 17 and 18 are electrically insulated from housing 10 by means of insulators 24 and 25 while being electrically connected by means of connections 26 and 27 to the frequency determining circuits of transmission oscillators 12

and 13, respectively. Gravity sensitive member 16 is also connected to the frequency determining circuits by means of connection 28 so that proportional frequency variations may be made in the transmission oscillators 12 and 13 from motion of gravity sensitive member 16 with respect to stationary members 17 and 18 as described above.

In Figure 3 is shown a simplified schematic wiring diagram of a transmission oscillator in which the variable frequency output required may be obtained. Such an oscillator is of the vacuum tube type and provided with vacuum tube 39, a frequency determining circuit consisting of paralleled inductance 40 and capacitance 41 connected between ground 42 and control grid 43. The frequency of oscillation is determined by the values of inductance and capacitance in this circuit according to

$$f = \sqrt{\frac{25330}{LC}}$$

in which f is the resonant frequency in megacycles, L the inductance in microhenries, and C the capacity in micromicrofarads.

Part of the capacitance of the circuit is included between stationary member 44 tapped onto inductance 40 and corresponding to either member 17 or 18 of Figure 1 and gravity sensitive member 16. Changes in the relative position of gravity sensitive member 16 with respect to stationary member 44 of Figure 2 changes proportionally the capacity of the frequency determining circuit causing a frequency change predictable from the equation given above.

Power is supplied to filament 45 provided by battery 46, screen grid voltage by battery 47, and plate voltage by batteries 48 and 49 in series. Switch 42a serves to disconnect power from filament 45 and the plate circuit. The electrical oscillations are amplified so that electrical current and voltage variations are obtained from the oscillator in the output circuit. The output circuit includes plate or anode 49, coupling capacitance 50 corresponding to either capacitance 31 or 32 in Figure 1, radio-frequency choke 51, and connections of these elements to each other and the power sources. It also includes connections 52 and 53 with shorting bar 54 for introducing an audio-frequency modulation to identify the signal obtained.

Referring now again to Figure 1, energy of variable frequency is conducted from transmission oscillators 12 and 13 by means of connections 29 and 30 containing coupling capacitances 31 and 32 respectively to connection 33. Energy is conducted therefrom by means of suspension line 11 to the surface where the inclination of the exploration instrument is determined from frequency or frequency change measurements with frequency measurement apparatus well known in the art such as accurately calibrated radio receivers, heterodyne frequency meters and the like as indicated generally in Figure 18. Conventional radio-frequency amplifiers may be added to the oscillator to increase the amplitude of the variable frequency signal obtained if desired.

Changes in capacity for frequency variation may also be obtained using the conventional plate-type variable capacitances shown in Figure 4. In this modification, the two condensers 55 and 56 are oriented at an angle to each other and are actuated by gravity sensitive members 57 and 58, respectively. Each may be connected to the frequency determining circuit of an elec-

trical oscillator as described above, and the frequency changes resulting correlated with inclination. Conveniently the axes of capacitor rotors 59 and 60 are at an angle of about 90° to each other, although other angles may be used.

Since two transmission oscillators are employed, as shown in Figure 1, and so they may be conveniently operated at approximately the same frequency, a means is provided to differentiate the signal of oscillator 13 from that of oscillator 12. This is accomplished by providing modulation oscillator 14 which modulates the signal from oscillator 13 at an audio-frequency for example. The modulation oscillator in this modification has another function if desired, or a separate means may be provided, for continuously indicating the orientation of the exploration instrument with respect to a given geographic direction so that the indication of inclination given by the transmission oscillators frequency variation may be interpreted properly. In one modification of the invention, the frequency of the audio-modulation may be varied in accordance with the azimuth indicated by gyro member 20 which may be preset at the surface.

In Figure 5, a schematic wiring diagram of a modulation oscillator is shown which is capable of differentiating the signals of the two transmission oscillators as well as indicating the geographic orientation of the exploration instrument in the subsurface. The modulation oscillator is of the vacuum tube type and generates a variable audio-frequency signal to modulate the signal generated by either one of the transmission oscillators. The frequency of the oscillation is dependent largely upon the frequency determining circuit comprising inductance 61, capacitance 62 and resistance 63. This circuit is connected to vacuum tube 64 which amplifies the oscillation. The output circuit comprising plate or anode 65, output transformer 66, plate power supply battery 67, and electrical connections joining these components with each other delivers energy in the form of an electrical oscillation at an audio-frequency to output terminals 68 and 69. The shorting bar 54 shown in Figure 3 is removed from terminals 52 and 53 which are connected to terminals 68 and 69, respectively, shown in Figure 5. In the latter figure, output transformer 66 is provided with a parallel variable resistance 70 which permits a controlled amount of energy at an audio-frequency to be introduced into the signal of one of the transmission oscillators. The presence of this audio-modulation is readily detectable on the transmission oscillator signal in a suitable receiver and one signal therefore may be differentiated from the other.

A constant frequency of audio-modulation is all that is needed for signal differentiation, however, a means for indicating orientation of the exploration instrument in the subsurface with respect to a geographic direction is necessary for proper interpretation of the borehole inclination data obtained from measurement of the variable frequency of the transmission oscillators. This azimuth data may be transmitted from the exploration instrument in the form of a variable audio-frequency modulation of the signal from one of the transmission oscillators. In Figure 5, resistance 63 is shown connected in series with the frequency determining circuit and it has the effect of lowering the oscillation frequency as the resistance is increased. For the oscillator shown where inductance 61 has a value of about 1.2

henries, capacitance 62 a value of about 0.150 microfarad, and resistance 63 is variable from zero to about 5,000 ohms, the audio-frequency range will be from about 80 to about 400 cycles per second.

Referring again to Figure 1, gyro member 20 is provided with rotor 34 and power supply 35. If desired, power may be applied through a commutator from power supply chamber 23. Bearings 21 and 22 permit gyro member 20 to maintain a given preset azimuth while housing 10 of the exploration instrument may turn about its longitudinal axis. Gyro member 20 is provided with sliding contact 36 which rests on the resistive element of circular electrical resistor 37 which is integrally attached to and rotates with housing 10 by attachment to lateral divider 38. This resistor is resistance 63 shown in Figure 5. As rotative motion occurs between gyro member 20 and housing 10, sliding contact 36 joins circular resistor 37 in a different position. A change in the electrical resistance of resistor 37 included between the point of sliding contact 36 and one terminal results. The electrical connection of sliding contact 36 with the modulation oscillator may be made through bearing 21 or through a commutator not shown. This change in resistance with rotary motion of the exploration instrument serves to vary the frequency of the modulation oscillator proportionally as described above. Detection of the frequencies of the two transmission oscillators and that of the modulation oscillator accurately determines the inclination of the borehole from the vertical as well as the azimuth of the incline.

With gyroscopic control of the azimuth determination, gyro member 20 of Figure 1 may be preset at the surface prior to subsurface exploration with the instrument to a known magnetic or geographic azimuth. Subsequent rotation of housing 10 with respect to gyro member 20 which maintains a constant geographic direction will cause the resistance between contacts 71 and 72 in Figure 6 to change. In Figure 6, a frequency of audio-modulation equivalent to zero resistance will indicate a certain azimuth, south being shown. Other azimuths are indicated as movable contact 73 increases or decreases the resistance between contacts 71 and 72 which is used to vary the frequency of audio-modulation as described above.

In Figure 7 is shown a modification of the apparatus of this invention in which gyroscopic member 74 maintains stationary members 75 and 76 in a fixed geographic orientation while any rotation of the exploration instrument housing during passage through a borehole may occur. Such rotation in this modification has no effect on the inclination determinations. Stationary members 75 and 76 are made part of the frequency determining circuits of two transmission oscillators such as described in connection with Figure 3. Gravity sensitive member 77 is common to both frequency determining circuits and the inclination is detected in the manner described above. A modulation oscillator is not strictly necessary if the transmission oscillators have sufficiently different frequency ranges that these do not overlap during operation. Should both oscillators have the same frequency when the instrument is in a vertical position, then the modulation oscillator is provided to differentiate one signal from the other.

In Figure 7, gyro member 74 is supported on bearings 78 and 79 and contains rotor 80. Power

to actuate the rotor as well as connections for members 75 and 76 are preferably brought through commutator 81. Power for rotor operation may be brought through contacts 82 and 83 at bearings 18 and 19, respectively.

A plan view of the apparatus of Figure 7 is shown in Figure 8 in which gyro member 80 is shown with stationary members 75 and 76 arranged at an angle θ of 90° to each other adjacent to gravity sensitive member 17. The gyro may be preset to align stationary member 75 in a north-south plane and member 76 in an east-west plane. Frequency change determinations are therefore readily convertible into inclination vectors 84 and 85 giving vector 86 shown in Figure 9. This vector shows the degree of inclination by its length and the azimuth. In this instance where one of the stationary members is disposed in a north-south plane, angle α shown in Figure 9 is zero. In any modification, angle α is known and preset prior to introduction of the instrument into the hole and angle θ_1 or θ_2 is the angle between the stationary members as described above.

Where gyro control of the stationary members is not employed, the frequency change of one transmission oscillator having a stationary member at point 87 in Figure 9 determines the position of the gravity sensitive member along an arc 88 or another arc having the same center. The frequency change of the second oscillator having a stationary member at point 89 spaced θ_2 degrees from point 87 determines the position of the gravity sensitive member as on an arc 90 or one having its center at point 89. The intersection of these arcs locates point 91. A vector 92 drawn from point 93, the center corresponding to the vertical position of gravity sensitive member, to point 91 shows the degree of inclination by its length and the direction by its angle with respect to other means such as the audio-modulation oscillator frequency variation or a gyro member determines angle α and the inclination and direction is completely determined.

In Figure 10 is shown an illustration of the changes in transmission oscillator frequency with inclination in various directions. In this diagram f_0 represents the frequency of these oscillators in the vertical position. When the instrument is inclined in a direction to move the gravity sensitive member away from both stationary members, decreasing the capacitances, the frequencies rise to values depicted by f_n for the nonmodulated oscillator and f_m for the modulated oscillator. The frequency change vectors 95 and 96 correspond to vectors of motion of the gravity sensitive member. The motion vectors determine the magnitude and direction of the movement of the gravity sensitive member and determine the magnitude and azimuth of the inclination. Frequency changes to values lower than f_0 indicate that the capacity between the particular stationary member corresponding to that signal and the gravity sensitive member is increased by movement to decrease the distance between the two members. Vector 97 gives a measure of the inclination giving this movement.

The method and apparatus of this invention which involves the variation of frequency generated by an electrical oscillator may be applied to the obtaining of other desirable physical data from the subsurface. According to the methods described hereinafter subsurface temperatures, pressures and depths may be determined.

Referring now to Figure 11 a cross-sectional

view of housing 98 is shown provided in the lower portion thereof with openings 99 by means of which the subsurface pressure is applied directly to portions of apparatus within housing 98. Chamber 100 is provided between dividers 101 and 102 and inductance 103 is suspended therein. Conductors 104 and 105 connect inductance 103 to other portions of the frequency determining circuit in an electrical oscillator described above but not shown in this figure. Bellows 106 attached to divider 102 is exposed on the under side to the subsurface pressure and on the upper side is connected directly to metallic slug 107 by means of rod 108. Changes in subsurface pressure cause bellows 106 to expand and contract thereby moving slug 107 to different positions within inductance 103. Such a variable inductance is known as a permeability tuned inductance and the frequency of the electrical oscillator is thereby varied in accordance with the subsurface pressure. If metallic slug 107 is fabricated from a ferrous alloy such as iron, steel, an iron nickel alloy or the like, the resonant frequency of the oscillator decreases as the slug is moved into the coil; whereas copper or copper alloy slugs cause the resonant frequency to increase as the slug is moved into the coil. Either type of slug may be employed with equal success and a choice will depend largely upon particular circumstances.

In Figure 12 another modification of the apparatus just described is shown in which changes in frequency of the electrical oscillator with subsurface pressure are effected by changing the actual physical dimensions of the inductance in the manner of a spring. Inductance 103 is caused to expand and contract as bellows 106 moves under the influence of external pressure applied to the inner portion thereof via holes 99 in housing 98. Inductance 103 is connected to the frequency determining circuit of an electrical oscillator whereby changes in subsurface pressure acting indirectly on inductance 103 cause the frequency of the oscillator to vary. Increases in pressure in this particular modification causing inductance to increase while decreases in pressure cause the inductance to decrease while the frequency of the oscillator decreases and increases, respectively. The same parts of apparatus shown in Figure 12, 13 and 14 are numbered identically with those in Figure 11.

Referring now to Figure 13 a modification of apparatus is shown in which subsurface pressure changes indirectly actuate a capacitor connected to the frequency determining circuit of an electrical oscillator. Housing 98 is provided with divisions 101 and 102, in the lower of which bellows 106 is attached. A capacitor having stationary electrode 109 and movable electrode 110 is provided, the latter electrode being directly attached by means of rod 108 to bellows 106. Connections 104 and 105 connect the variable capacitor directly to the frequency determining circuit of an electrical oscillator whereby frequency variations in accordance with subsurface pressures are obtained. The particular advantage of this modification resides in the greater frequency change per unit degree of expansion of bellows 106 at high pressures wherein the bellows 106 is extended. A particular type of bellows may be employed therefor which is operable over a wide range of pressures so that small degrees of bellows extension in the higher pressure ranges yield readable frequency changes.

The method and apparatus of the present in-

vention may be applied to the measurement of subsurface temperatures as is shown in Figure 14. Housing 98 is provided with openings 99, divider 102, and with additional opening 111 through which fluid may enter to leave via openings 99. The frequency determining circuit of an electrical oscillator is positioned in chamber 112 above divider 102 and contains inductance 113 provided with connections 114, 115 and 116. A capacitance 117 is connected in parallel with inductance 113 and is preferably a capacitor having a zero temperature-capacitance coefficient so that the frequency determining circuit present in chamber 112 is unaffected by temperature. Another capacitor 118 is positioned directly in line with opening 111 and is connected by means of connectors 119 and 120 in parallel with capacitor 117. Capacitor 118 is that type having a positive or negative temperature-capacitance coefficient so that as the temperature is varied the capacitance and the frequency of the electrical oscillator change. In the case of where capacitor 118 has a positive temperature coefficient, increases in temperature will bring about decreases in oscillator frequency. Where capacitor 118 has a negative temperature coefficient, increases in oscillator frequency result from increases in temperature. It is preferable that the ratio of capacitance of capacitors 118 and 117 be such that changes in temperature directly acting upon capacitor 118 result in sufficient frequency change that the desired degree of temperature determination is obtained. If desired, the entire capacitance of the frequency determining circuit may be lumped in capacitor 118 and capacitor 117 may be dispensed with. At least part of the capacitance in the circuit must have a temperature coefficient different from zero.

The frequency determining circuits herein described in conjunction with Figures 11 through 14 correspond to the frequency determining circuit shown in Figure 3 which consists of inductance 40 and capacitor 41. The electrical oscillator, also described herein as a transmission oscillator shown in Figure 3 is also applicable to the apparatus and methods described in Figures 11 through 14. These apparatuses are preferably operated in conjunction with apparatus to continuously determine or record the depth of the instrument from the surface. These apparatuses may also be operated either by moving them continuously through a subsurface opening such as a well bore or by lowering them to different levels at which all motion is stopped while the pressure, depth, or temperature determination is made. In logging a borehole during the process of drilling or under other conditions where the borehole contains a fluid of known density, pressure measurements according to the methods described above may also be employed to measure depths.

The apparatus shown in Figures 11, 12 and 13 preferably are constructed using a frequency determining circuit having a zero temperature coefficient so that pressure alone effects the frequency of the transmission oscillator. If desired, separate oscillators may be employed according to the methods herein described to separately measure pressure and temperature in one logging operation.

Referring now particularly to Figure 15, a vertical cross section of another modification of the exploration instrument according to this invention is shown in which the well bore inclination

actuates a pair of gravity sensitive members which in turn actuate a pair of circular resistors similar to the type described in Figures 5 and 6. Housing 121 is provided with upper divider 122 and lower divider 123 forming chamber 124 in which the gravity sensitive members and their associated equipment are contained. If desired, chamber 124 may be filled with a liquid to dampen periodic oscillations of the pendula as described above. A gyro member 125 provided with gyro housing 126 is supported by bearings 127 which may be circular ball or roller type bearings on supports 128 and 129. Power is supplied to the electrically driven gyro member 125 via commutators 130 and 131 through connections 132 and 133. Structure 134 upon which circular resistors 135 and 136 are supported and insulated therefrom is indirectly attached to gyro housing 126 to rotate therewith relative to housing 121. A plan view of such a circular resistor is shown in Figure 16 in which winding 137 is provided with contacts 138 and 139 and movable contact 140. In the present modification contact 140 is moved with respect to winding 137 by means of a pair of bevel gears 141 and 142. Bevel gear 142 in turn is actuated by gravity sensitive member 143. By employing a pair of circular resistors with the associated contact, bevel gear, and gravity sensitive member equipment described and spacing them at an angle to one another as above described such as 90° an exact determination of inclination of the instrument with respect to a vertical line may be obtained. The two gravity sensitive members 143 and 144 shown in Figure 15 are restricted to movement in one plane each at right angles to each other. Further, they are supported directly upon the gyro member by means of which a constant angle between said planes and a given geographic direction may be maintained. Therefore, by presenting the planes in which the gyro members may move to correspond with a north-south and an east-west plane, the actual inclination as well as the azimuth may be obtained through direct or indirect readings of the circular resistances followed by a vector summation of them. Connections to circular resistances 135 and 136 are made via commutator 145 provided with contacts 146 shown in Figure 15.

It is preferred that when the apparatus is in a vertical position movable contact 140 shown in Figure 16 is provided with electrical connection 147 in such a position that the electrical resistance of resistor 137 between movable contact 140 and contact 138 be the same as the resistance between movable contact 140 and contact 139. That is, movable contact 140 is electrically midway between the ends of circular resistor 137. Thus, as the gravity sensitive member 143 moves in plane 148 in response to changes in inclination, the resistance between contact 147 and either of contacts 138 and 139 varies accordingly to provide a variable voltage or current from which the degree of inclination in that plane may be directly determined from the constants of the system by calculation or by previous calibration.

As is indicated in Figure 15 a pair of circular resistances with gravity sensitive members to actuate them may be positioned in planes at right angles to one another to obtain electrical indications of inclination, the vector sum of which directly indicate the azimuth and degree of inclination. The variable voltages thus obtained, which may be either alternating current or direct current voltages, may be employed to deflect the electron beam of the cathode ray oscilloscope by

applying the voltage from one resistor to the horizontal deflection plates and the other voltage obtained to the vertical deflection plates, for example.

One modification of such an embodiment is shown in Figure 17 in which the cathode ray tube screen 149 is shown. In this modification a gyro control system is employed in the apparatus whereby one gravity sensitive member moves in a north-south plane and the voltage therefrom is applied to the vertical deflection plates of the tube. The other gravity sensitive member is permitted to move in an east-west plane and the voltage from the associated resistor is applied to the horizontal deflection plates of the tube. A linear change in voltage may be obtained with inclination in each plane and a linear deflection of electron beam with which in deflection voltage may be represented by vector 150 in the north-south plane and by vector 151 in the east-west plane. Actually neither of these vectors are indicated on the cathode ray tube screen. However, point 152 is indicated as a bright spot denoting the point at which the deflected electron beam impinges on the screen and the vector summation is automatically made. A line drawn from screen center 153 to point 152 gives inclination vector 154 the length of which is the exact measure of the degree of inclination. The angle θ included between inclination vector 154 and the north-south line is the azimuth of the inclination. In this manner a recordable representation of the azimuth and degree of inclination is obtained and it may easily be photographed in conjunction with a depth reading device whereby a continuous photographic record of the azimuth and the inclination and the depth may be obtained. For such a photographic record a motion picture type camera is preferred, particularly where the exploration instrument is continuously moved through the borehole or other subsurface opening while the inclinations and depths are measured. Where the instrument is stopped at each level where an inclination determination is desired, an ordinary camera preferably modified to wind films automatically between exposures may be employed to photographically record the visual indications of the cathode ray screen and the reading on the depth indicator.

In another preferred modification of this embodiment of the invention the variable resistance above described in connection with Figures 15 and 16 are applied to a pair of modulation oscillators operating in the audio-frequency range. The change in resistance causes the frequency of the audio-oscillation to change thereby indicating the inclination in a given plane. The audio-oscillator so employed may be one like that described in connection with Figure 5 and is employed to modulate a transmission oscillator similar to that described in connection with Figure 3. The transmission oscillator or oscillators in this case may be of the constant frequency type and the data from which the degree and azimuth of inclination is obtained is transmitted via an electrical conductor from the subsurface in the form of a variable frequency audio-modulation of the radio-frequency transmission oscillator.

In the description of the embodiments of the present invention variable frequency oscillators operating in the radio-frequency range have been described and it is intended that the radio frequency range so indicated be the same as the radio-frequency range well known to those in the art of radio communication, for example, from a

lower frequency of about 15 kilocycles to high frequencies of the order of 5,000 megacycles and higher. Preferably the operational range of radio-frequency is included between about 500 kilocycles and about 500 megacycles, although these specific ranges are not intended to limit the present invention. The audio-frequency range in which the variable frequency modulation oscillator operates preferably generates oscillation in the well known audio-frequency range between about 15 cycles and about 15,000 cycles per second. However, modulation frequencies lower or higher than the limits given above may be used in conjunction with instruments capable of measuring such frequencies. In the case of the audio-frequency range, particularly those frequencies between about 100 cycles per second and 5,000 cycles per second, the measurement may be made with bridge type instruments wherein an oscillation of known frequency is compared by ear to a beat frequency of zero whereby the unknown modulation frequency is determined.

A particular embodiment of the present invention has been hereinafter described in considerable detail by way of illustration. It should be understood that various other modifications and adaptations thereof may be made by those skilled in this particular art without departing from the spirit and scope of this invention as set forth in the appended claims.

I claim:

1. An apparatus for determining the deviation of a borehole from the vertical which comprises an elongated fluid tight housing, a suspension means therefor, two radio-frequency oscillators within said housing, a single movable gravity sensitive electrode connected to the frequency determining circuit of both of said oscillators, a pair of separate stationary electrodes angularly disposed adjacent said gravity sensitive electrode forming a pair of variable capacitors, means connecting one each of said stationary electrodes to said frequency determining circuits of said radio-frequency oscillators, means for electrically transmitting radio-frequency oscillations from said housing to the surface, and means for measuring each of said radio frequencies to determine said deviation.

2. An exploration instrument for continuously logging the vertical deviation of a borehole drilled into the earth which comprises an elongated fluid-tight housing, a suspension cable therefor, means for moving said housing through said borehole, a movable gravity sensitive electrode within said housing, two stationary electrodes angularly disposed adjacent said movable electrode and insulated therefrom forming a pair of variable capacitors having a common movable electrode, a radio-frequency electrical oscillator connected at its frequency determining circuit to each of said stationary electrodes and to said movable electrode, an audio-frequency electrical oscillator of continuous and variable frequency output, power supply means for said oscillators, means for modulating the oscillation from one radio-frequency oscillator with the variable audio frequency oscillation from said audio-frequency oscillation, means for varying the frequency of said audio frequency oscillator in accordance with the orientation of said instrument with respect to a given geographic direction, means for electrically transmitting said oscillations through said borehole, and means to measure the frequency of said oscillations sub-

stantially at the earth's surface to determine the magnitude and the azimuth of said vertical deviation.

3. An apparatus for determining the inclination of bore holes which comprises an elongated fluid-tight housing provided with two transmission oscillators and one modulation oscillator, said transmission oscillators having a frequency variable in the radio frequency range and said modulation oscillator having a frequency variable in the audio frequency range, a frequency determining circuit for each of said transmission oscillators comprising an inductance and a variable capacitor, a gravity sensitive movable electrode as a common electrode in each of said variable capacitors, a pair of stationary electrodes disposed in spaced relation to said gravity sensitive electrode forming said variable capacitors, a gyro member mounted within said housing, said stationary electrodes supported by and insulated from said gyro member whereby said stationary electrodes are adapted to be maintained in a uniform orientation with respect to a given geographic direction, means connecting said modulation oscillator to one of said transmission oscillators and means for measuring the frequencies of said transmission oscillators and said modulation oscillator to determine the azimuth and the degree of inclination of said bore hole.

4. An apparatus for determining the inclination of boreholes which comprises an elongated fluid tight housing provided with two transmission oscillators and one modulation oscillator, said transmission oscillators having a frequency variable in the radio-frequency range and said modulation oscillator having a frequency variable in the audio-frequency range, power supply means for said oscillators, a frequency determining circuit for each of said

transmission oscillators comprising an inductance and a variable capacitor, a gravity sensitive movable electrode common to each of said capacitors, a pair of stationary electrodes in spaced relation to said gravity sensitive electrode forming said variable capacitors, a gyro member within said housing, a circular variable resistor adapted to be varied by the position of said gyro member in relation to said housing, said resistor being adapted to vary the audio frequency of said modulation oscillator continuously in accordance with the geographical orientation of said housing, power supply means for said gyro member, means connecting said modulation oscillator to one of said transmission oscillators and means for measuring the frequencies of said transmission oscillators and said modulation oscillator to determine the azimuth and the degree of inclination of said borehole.
